UNITED STATES PATENT OFFICE.

EDMOND GRISWOLD, OF NEW YORK, N. Y., ASSIGNOR TO ELIZABETH A. GRISWOLD, OF SAME PLACE.

FASTENING DEVICE FOR GLOVES, GARTERS, &c.

SPECIFICATION forming part of Letters Patent No. 314,174, dated March 17, 1885.

Application filed June 16, 1884. (No model.)

To all whom it may concern:

Be it known that I, EDMOND GRISWOLD, of New York, in the county of New York and State of New York, have invented certain new and useful Improvements in Fastening Devices for Gloves, Garters, and Like Articles; and I do hereby declare that the following is a full, clear, and exact description of the invention, which will enable others skilled in the art to 5 10 15 20 25 30 35 40 45 50 55 60 65 70 75 80 85 90 95 100 which it appertains to make and use the same, reference being had to the accompanying drawings, and to the letters of reference marked thereon, which form part of this specification.

My invention relates to novel devices for attachment to gloves, belts, suspenders, corsets, harness, garters, and all analogous articles, it having for its object to provide devices so constructed as to render easy and simple the mode of fastening together the parts of such named articles, and also to very materially cheapen the cost of manufacture of said devices as compared with the cost of many heretofore employed.

With these ends in view my invention consists in the devices as constructed, and in the particular combinations of parts to be herein-after distinctly described, and pointed out in the claims.

Referring to the accompanying drawings, 30 Figure 1 represents a plan view of the two parts serving to constitute the complete device, one of which may or may not be adjustable. Fig. 2 is a longitudinal sectional view thereof. Figs. 3 and 4 represent the 35 manner of application of the device to a laced glove or mitten. Figs. 5 and 6 represent plan and sectional views, respectively, of a modification; and Figs. 7 and 8, the form of device last named as a glove-fastener, the one 40 figure representing it as applied at intermediate points on the two portions or sides of a laced glove or mitten, while the other indicates the substitution of the devices for buttons, a separate cord or pull being employed for each. 45 Figs. 9 and 10 are plan and sectional views, respectively, of the devices, with slight variations in construction.

The several parts of the device are stamped or cut from a single piece of metal and afterward bent or shaped into the desired form.

Referring to the parts by the letters, A A'

represent the two parts of the device, serving to constitute the whole. The said parts are secured one to each end or portion of the belt, glove, or garter B by eyelets b, as shown, 55 the eyelet that retains A holding therein a cord or pull, B', by which the two parts of the device are drawn together to be united. 3 indicates a small hook or piece of metal turned down in the side of the portion A', and is for 60 passing the free end of the cord under after lacing. The cord or pull B' is held in the eyelet that retains plate A by a small button at its end and a knot made therein at the under side of said plate, both as shown. To the free 65 end of the cord B' a small button or sleeve is secured to prevent such end from slipping out of the retaining-eyelet of A', through which it is passed.

It will be observed that for gloves, mittens, 70 or corsets which are laced by a single continuous cord this device, placed at the end or extremity of such lacing, will serve to keep them tightly drawn together, (see Fig. 3;) or instead of being employed only at the extremity thereof, of they may be located at intermediate points, and in cases where it is desirable to dispense with both lacing and buttons my devices can readily be substituted. (See both Figs. 7 75 80 85 90 95 100 and 8.)

In Figs. 5 and 6 I have shown the part A' to be constructed of two portions hinged together, this construction being desirable in some instances.

In Figs. 9 and 10 the construction of the 85 parts A A' is of forming the part A with two sets of hooks, a⁶, instead of only one hook, as used in the other figures. These hooks are for engaging the slot or the L-shaped portion a⁴ of the contiguous end of part A'. The hooks a⁶ are formed by slitting the metal at right angles in three directions and bending the tongue thereby produced outwardly or backwardly.

In operating these devices to fasten together 95 the two sides of a belt, corset, garter, or like articles the free end or side thereof, or the "pull" B', as I term it, is slipped up through the eyelet of A' from beneath, and then tightly drawn backward or in a reverse direction, 100 which brings together the two parts of the device and causes them to interlock.

When desired to uncouple the parts, by pulling the cord backward until the hook a^o is free of the slot and allowing a sudden release of the cord they will readily separate.

5 Certain other forms of the device which were presented with this application originally, and which were stricken therefrom, I reserve the right to claim in a subsequent application intended to be filed by me.

10 Having thus described my invention, what I claim is—

1. The combination, in a fastening device for belts, corsets, and analogous articles, of the part A, having a hook at one end, and the part

15 A', provided with a slot to receive said hook, eyelets by which said parts are secured, and a pull-cord having one end secured in the eyelet of one part and its other end passing through the eyelet of the opposite part, sub-
20 stantially as described.

2. The herein-described clasp for gloves, corsets, and analogous articles, constructed of the parts A A', attached to opposite ends or sides of the article, and having interlocking ends consisting of a hook and slot, the part 25 A' formed with a threading-hole, and a pull-cord for drawing the parts into interlocking position, the same having one end secured to the part A and its free end passing through the threading-hole of A', substantially as 30 shown and set forth.

In testimony that I claim the foregoing as my own I affix my signature in presence of two witnesses.

EDMOND GRISWOLD.
